(57) **CLAIM**

The ornamental design for a snack food container, as shown and described.

DESCRIPTION

FIG. 1 is a perspective view of the snack food container showing our new design;

FIG. 2 is a front elevation view thereof, with the rear elevation view, right side elevation view, and left side elevation view, all mirror images of the front elevation view thereof;

FIG. 3 is a top plan view thereof; and,

FIG. 4 is a bottom plan view thereof.

The broken line showing of FIG. 4 is for illustrative purposes only and forms no part of the claimed design.
